UNITED STATES PATENT OFFICE.

FREDERIC PAYSON REED, OF EAST ORANGE, NEW JERSEY, ASSIGNOR, BY MESNE ASSIGNMENTS, TO CHARLES C. ORCUTT.

DRYING MACHINE.

Application filed May 18, 1921. Serial No. 470,667.

To all whom it may concern:

Be it known that I, FREDERIC PAYSON REED, a citizen of the United States, residing at East Orange, in the county of Essex, 5 State of New Jersey, have invented certain new and useful Improvements in Drying Machines; and I do hereby declare the following to be a full, clear, and exact description of the invention, such as will enable 10 others skilled in the art to which it appertains to make and use the same.

My invention is an improvement in drying machines, of the character shown and described in applications Serial Nos. 434,231 15 filed February 6, 1920, 434,321 filed December 21, 1920, and 456,857 filed March 30, 1921, and relates especially to an improved form of supporting means for the material to be dried, as for instance, the web from 20 a paper making machine during its passage through the drying machine.

In drying machines now in use, the web is supported between drying felts and is drawn over a series of heated cylinders. 25 The felts fit closely against the opposite faces of the web, and the drying of the web is for the greater part by absorption through the felts, the moisture absorbed being afterwards evaporated from the felts. When the 30 felts are in contact with the cylinders, or in proximity thereto, the moisture is driven off in the form of vapor by the heat of the cylinders. This vapor is afterwards condensed upon the cooler portions of the web, 35 and of the felts. Hence, there is a succession of alternating periods of drying and moistening, and the drying is a slow expensive operation. Furthermore, to permit drying without scorching of the web, the 40 temperature of the drying cylinder must be carefully controlled within relatively narrow limits, and the highest temperature best suited to quick drying may not be used.

The object of the present invention is to 45 provide a supporting means for the web, of such nature, that a free circulation of air is provided between the web and the carrying means, in every direction, while at the same time the web is supported at points 50 closely set, though of relatively restricted area, to expose the largest possible amount of web surface to the drying action of the dryer.

In the drawings—
86 Figure 1 is a sectional view of a drying

unit provided with the improved supporting means. Figure 2 is a partial top plan view. Figure 3 is an enlarged plan of a supporting roller. Figure 4 is a front view of the roller with the support in section. Figure 60 5 is a view similar to Figure 3, showing another embodiment of the invention. And Figure 6 is a view similar to Figure 4 of the said embodiment.

In Figure 1, there is shown one unit of the 65 drying machine forming the subject matter of application Serial No. 356,669 filed February 6, 1920. This unit comprises a casing 1, supported by a suitable frame 2, having within the same any suitable form of 70 drying means. At each end of the casing a roller 3 is journaled on parallel axes. Other rollers 4 are journaled parallel with the rollers 3, between the same, and the rollers 4 are spaced apart from each other and 75 from the rollers 3. These rollers 3 and 4 support the upper run of an endless carrier for the paper web. The endless carrier is composed of a number of independent strands 5, which may be in the form of 80 bands, as shown in Figs. 1 to 4 inclusive, or in the form of wires, as shown in Figs. 5 and 6. Each of these strands is an endless belt, and they are supported by the rollers 3 and 4, and by rollers 6 and 7, arranged beneath the casing 1. The roller 6 is at the center of the casing 1, while the rollers 7 are at the ends, just below the rollers 3. The rollers 7 are tension rollers, being journaled in the ends of arms 8, which are pivoted to the frame 2 as shown, and counter weights 9 are arranged on the arms. By means of these counter weights the tension upon the endless conveyor constituted by the strands 5, may be varied. The rollers 3 are 85 grooved annularly as shown at 10, to receive the bands 5, and the said grooves are of a depth corresponding to the thickness of the bands, so that the outer surfaces of the bands are flush with the peripheral surfaces of the 90 rollers. The band receiving grooves 10 are spaced apart from each other a distance substantially equal to the width of a band, and the rollers 4 may be also grooved as shown in Fig. 2 if desired. In Fig. 5 there is 95 shown a construction wherein the supporting means is in the form of endless belts 11, or wires, the rollers 12 corresponding to rollers 3 and 4, being annularly grooved as shown at 13, to receive the wires. The wires 110

11 are spaced apart from each other a distance corresponding approximately to the spacing of the bands 5, and they may be supported in the same manner as the bands 5, in Figure 1. Either construction provides a supporting means for the paper web, or other article to be dried, which exposes the largest possible amount of the web surface, engaging the web over surfaces which are 10 relatively restricted and relatively close set. Thus the web will be supported throughout its extent, to prevent buckling, warping and the like, while at the same time it will be held from the plates 14, forming the top of 15 casing 1, a distance such that there will be no danger of scorching, because of the free circulation of air between the plates and the web. With the usual form of dryer, the web is separated from the source of heat, that is, 20 the plates 14, by a solid damp felt, through which, by conduction, the heat passes to the paper. With the improved supporting means, the air heated by the plates 14 may pass directly to the face of the web, and the 25 plates may be heated to a very high temperature without danger of scorching the web. Neither is the web subject to strains, such as may arise from changes in the usual hot, moist carrying apron of felt, and there 30 are no smooth highly heated surfaces to which the paper may adhere. The improved supporting means for the paper web may be of any suitable non-combustible material, as for instance, asbestos, copper, brass, steel or 35 aluminum. When bands are used, they may be of any of the materials specified. When

wire is used, it is preferably of copper, brass or steel.

I claim:

1. In a drying machine means for supporting the web to be dried comprising a series of endless flexible metal strands arranged alongside of each other with the upper runs of the strands in the same horizontal plane, and means for supporting said 45 strands in such manner that they may be moved by the paper as it travels, or the paper may move over the strands.

2. In a drying machine means for supporting the web to be dried comprising a 50 series of endless flexible metal strands arranged alongside of each other with the upper runs of the strands in the same horizontal plane, means for supporting said strands in such manner that they may be 55 moved by the paper as it travels, or the paper may move over the strands, with the upper runs held in spaced substantially parallel relation.

3. In a drying machine, means for supporting the web to be dried, comprising a serial of endless flexible strands of non-combustible material, means for supporting the strands so that they may be moved by the web to be dried, said means comprising rollers grooved circumferentially to receive the strands and hold them in spaced relation, the strands being spaced from each other a distance corresponding substantially to the width of the strands. 60 65

In testimony whereof I affix my signature.
FREDERIC PAYSON REED. 70
